METHOD AND APPARATUS FOR ELECTRIC
DEHYDRATION OF EMULSIONSClaudius H. M. Roberts, Long Beach, Calif., as-
signor to Petroleum Rectifying Company of
California, Los Angeles, Calif., a corporation
of California

Application November 10, 1932, Serial No. 642,100

20 Claims. (Cl. 204—24)

My invention relates to the art of electrical treatment of emulsions, and finds particular utility in treating petroleum emulsions of the water-in-oil type so as to coalesce the water particles into masses of sufficient size to be economically separated from the oil. It should not be understood, however, that the invention is limited to this type of emulsion, for it finds utility in treating other types and kinds of emulsions and mixtures. For the purpose of clarity, the invention will be hereinafter described with particular reference to the treatment of petroleum emulsions without limiting myself thereto.

The conventional method of electrically dehydrating such a petroleum emulsion includes subjecting this emulsion to an electric field between a pair of electrodes. This electric field is set up by a high intensity alternating potential impressed across a pair of electrodes. In practice the wave form of such an alternating potential is substantially sinusoidal.

The present invention includes among its objects the utilization of a potential having a steep wave-front, such a potential having been found to be very effective with certain types of emulsions, certain of which are otherwise untreatable by electrical methods. This steep wave-front potential is preferably applied in the form of one or more surges which are very effective in coalescing the dispersed phase into masses of sufficient size to settle by gravity from the continuous phase or to be removed therefrom by other well-known separating methods.

Also included among the objects of the present invention is the utilization of a condenser to set up such a steep wave-front surge, the invention including both a method and apparatus for first charging this condenser and subsequently discharging it into the input circuit of the electrodes, whereby the surge is conducted to these electrodes and sets up a correspondingly high intensity field therebetween.

In the preferred embodiment of the invention the condenser is charged during the time that a potential difference is impressed across the electrodes and is discharged after this potential difference has been substantially reduced or removed. This is not, however, invariably necessary for in some instances the surge resulting from the discharge of the condenser may be superimposed on another potential continuously applied to the electrodes. Both systems fall within the scope of the present invention.

Other objects of the invention lie in the use of a switch means whereby the condenser can be

first charged and subsequently discharged, and also in the vibrator for operating such a switch means to periodically change the connections of the circuit.

So also the circuits utilized are of particular value when treating certain types of emulsions which are otherwise difficult or impossible of treatment by electric methods, it having been found that these circuits tend to decrease the tendency of the dispersed particles to form low resistance paths between the electrodes, which paths sometimes result in the consumption of excessive amounts of energy.

My experiments have also disclosed that a very desirable treating action accrues from the use of a compound electric field having both direct current and alternating current components. It has been further found that greatly improved results accrue in the treatment of certain types of emulsions if the compound field is so designed that the potential across the electrodes never becomes zero. With such a system the potential across the electrodes would be graphically represented by a curve lying entirely on one side of the zero or abscissa axis, no portion of the curve touching this axis. The result is that there is in effect a unidirectional potential applied to the electrodes at all times, thus permitting such a system to combine the advantages of alternating and direct current systems, and in some instances, to combine with the coalescing action a migrating action whereby the dispersed particles tend to migrate toward one or the other of the electrodes.

Such a compound field may be provided in a number of ways, but it is one of the objects of the present invention to utilize separate sources of direct and alternating potential, and to incorporate these sources in circuits which isolate the direct current from the source of alternating potential and vice versa.

Such a compound field system may even be used to advantage along with the steep wave-front surges previously described, and such a system falls within the scope of the present invention. If such a system includes a condenser, it will be found advantageous to charge and discharge the condenser by the source of alternating potential retaining the source of direct potential connected to the electrodes during the time that the condenser discharges, thus preventing the potential across the electrodes from reaching a zero value.

My experiments also show that the effectiveness of treatment is often dependent upon the

frequency of the alternating potential utilized, it having been found that by properly selecting the frequency, it is possible to utilize lower potentials than would otherwise be necessary.

- 5 These frequencies are ordinarily higher than the commercial frequency utilized in present dehydration methods, though somewhat lower than the radio-frequency range. It is another object of the present invention to utilize a frequency 10 particularly adapted to the emulsion undergoing treatment and to correspondingly control the potentials utilized.

The application of an alternating field tends 15 to elongate the dispersed particles in step with the alternating potential utilized, and it is a further object of the present invention to utilize a frequency which causes a maximum elongation or stress at the interface, this being usually accomplished when the frequency of the alternating potential is adjusted to resonance with the natural period of free vibration of the particles.

Further objects and advantages of the invention 25 will be made evident hereinafter.

Referring to the drawings,—

Fig. 1 is a wiring diagram illustrating one embodiment of the invention supplying both direct current and alternating current potentials to the treater.

30 Fig. 2 is a graphical representation of the direct current component.

Fig. 3 is a graphical representation of the alternating current component.

35 Fig. 4 is a graphical representation of the resultant field.

Fig. 5 is a wiring diagram illustrating an alternative system.

40 Figs. 6 and 7 are graphical representations of resulting field when the circuit shown in Fig. 5 is energized by a direct current potential.

Figs. 8 and 9 are graphical representations of the resulting field when the circuit shown in Fig. 5 is energized by alternating current potential.

45 Fig. 10 is a wiring diagram of an alternative form of the invention.

Referring particularly to Fig. 1, I have illustrated one form of well-known electric treater indicated in general by the numeral 10 and including a shell 11 which forms an outer electrode.

50 An inner electrode 12 is positioned centrally in the shell and is suspended from a suitable rack 13 supported by insulators 14. Emulsion may be introduced into a treating space 15 defined between the electrodes through a pipe

55 16. After undergoing treatment the emulsion is discharged through a pipe 17 into a settling tank 18 where the phases of the emulsion gravitationally separate, the oil rising to the top of the tank and being discharged through a pipe 19, and the water dropping to the bottom of the

60 tank and being discharged through a pipe 20. It will be clear, however, that other types of treaters may be utilized and that the particular type of treater shown need not be used. Thus,

65 certain other well-known types of treaters may be utilized in which the electric treatment and the separation take place in the same tank.

In this form of the invention it is desirable 70 to utilize a composite field in the treating space 15, and this is accomplished by the use of a source of unidirectional potential 25 and a source of alternating potential 26 respectively connected to the electrodes 11 and 12 in a manner to be

75 hereinafter described.

The source of unidirectional potential 25 is shown as including a motor-generator set comprising a motor 27 energized from a supply line 28 including a switch 29, this motor being connected to a direct current generator 30 including a shunt field winding 31 in series with a control rheostat 32 for controlling the output voltage of the generator. One terminal of this generator is connected to a conductor 33 which includes a switch 34 and is connected to the tank 18 which is in turn grounded. The other terminal of this generator is connected to a conductor 36 which conducts current to the inner electrode 12. An ammeter 37 is preferably placed in the conductor 36, as is also a choke coil 38, this choke coil preventing the alternating component of the field from reaching the generator 30 and detrimentally affecting the windings of the armature or field of this generator.

It has been found to be desirable in many instances to utilize a generator 30 having a rather pronounced ripple in its output voltage. The degree of ripple obtainable from a generator is, of course, dependent upon several factors, one of the most important of which is the number of commutator segments utilized. If desired a generator may be used which has a smaller number of commutator segments than the conventional types of generators at present in use. In Fig. 2 I have illustrated the unidirectional component of the potential applied between the electrodes from the generator 30, the line 39 indicating this potential. The magnitude of this potential is, of course, represented by the vertical distance between the line 39 and the zero axis 0-X.

It should not be understood, however, that I am limited to the use of a motor-generator set for setting up this unidirectional potential. It is entirely possible to use other devices. Thus, if a source of direct current is already available at the field installation, it is possible to utilize this for supplying the unidirectional component. In other instances it is possible to rectify the alternating potential supplied by the line 28 by the use of well-known rectifiers, such as those of the vacuum-tube or mercury-vapor type. With such rectifiers it is very easy to obtain the desirable ripple.

The source of alternating potential 26 is shown 50 as including a motor-generator set including an alternating current motor 42 directly connected to a direct current generator 43 which is used for exciting a field winding 44 of an alternator 45. By controlling the speed of the motor 42 in any 55 well-known manner by a device such as indicated by the numeral 46, the frequency output of the alternator 45 can be varied. Similarly, by controlling the voltage output of the generator 43 the output voltage of the alternator 45 can be 60 readily varied.

One terminal of the alternator 45 is connected to a conductor 48 extending to one blade of a switch 50. This conductor preferably includes an ammeter 51 and may include a commutating device 52 comprising a switch means for periodically breaking the circuit. Such a commutating means may be mechanically or electrically operated either in synchronism or out of synchronism with the alternating potential derived 70 from the alternator 45. The other terminal of the alternator 45 is connected to a conductor 54 which extends to another blade of the switch 50 and includes an overload circuit-breaker 55 there- 75

in. A choke coil 58 may be positioned in this conductor and acts as a variable reactance which can be used to regulate the current reaching the switch 50.

5 The switch 50 is connected to an input circuit 60 of the treater 10, this input circuit being shown as including a step-up transformer 61 having a primary winding 62 connected across the switch 50. A secondary or high potential winding 63

10 of the transformer is connected to the inner and outer electrodes through conductors 64 and 65 respectively. A condenser 66 is positioned in the conductor 64 and serves a dual function. In the first place, this condenser functions to block out

15 the direct current component of the resultant potential applied across the electrodes, thus preventing this direct current component from setting up a current through the secondary winding 63 of the transformer. In the second place, this

20 condenser acts as a storage means, being charged when the transformer 61 is energized and being subsequently discharged through the secondary winding 63 and to the electrodes 11 and 12 when the transformer is de-energized.

25 Fig. 3 illustrates a typical sinusoidal wave form developed by the alternator 45. It will be noticed that the line 10 representing this alternating potential extends both above and below the zero or abscissa axis O—X. However, the resultant potential applied to the electrodes includes both the alternating component shown in Fig. 3 and the unidirectional component shown in Fig. 2, the resultant potential being the additive result of these components and being shown 30 in Fig. 4. This resultant potential will be in the form of a curve 72 of general sinusoidal shape on which is superimposed the ripple developed by the source of unidirectional potential. This 35 type of combined high frequency and low frequency wave form is often desirable, regardless of whether or not the resultant curve lies entirely above the zero axis. However, in the preferred embodiment of the invention I have found it extremely desirable when treating certain types 40 of emulsions heretofore difficult or impossible to treat by electrical methods to so regulate the magnitude of the unidirectional and alternating potentials that the resultant curve 72 lies entirely above the zero axis O—X. This result can be 45 accomplished by supplying to the electrodes a unidirectional potential of greater magnitude than the peak potential of the alternating potential. Thus, during the operation of the treater there will be impressed across the electrodes at 50 all times a varying unidirectional potential, the minimum value of which is represented by the vertical distance between the line R—S and the zero axis O—X.

The desirable action accruing from such a system can be explained by considering the action which takes place on a water droplet suspended between the electrodes 11 and 12. This water droplet will be charged by induction due to its being positioned in an electric field. In addition, it will itself carry certain ionic charges which, in the absence of an electric field, will be uniformly distributed adjacent the interface. The application of an electric field will cause these charges to move to those portions of the droplet which are closest to the electrodes. Thus, the positive charges will be concentrated at one portion of the droplet and the negative charges will be concentrated at a diametrically opposed portion, the equatorial section being substantially free of such 75 ionic charges. The result is that the droplet will

be elongated in such a direction as to tend to bridge between the electrodes, or, in other words, in a direction parallel to the lines of force of the electrostatic field. An increase in the potential applied to the electrodes will increase 5 this elongation of the droplet, and a reversal of potential of the electrodes will cause a reversal of position of these charges on the droplet. Such a reversal in the position of the charges will never take place if the potential impressed across 10 the electrodes does not become zero. Thus, in the system shown, the droplet will tend to elongate in synchronism with the variations of the applied potential, and there will always be a unidirectional component of the field acting upon 15 the droplet. Since this droplet carries an inherent charge due to adsorbed ions from the oil, whose companion ions of opposite sign of charge are in the oil and free to move, the particle will thus be drawn toward one or the other of the 20 electrodes, depending upon the sign of the charge. It will thus be clear that in my system the particle is not only subjected to a field of varying intensity, but is also subjected to a unidirectional component which tends to set up a 25 migration of the droplet in the field. This dual action has been found to be very effective with certain types of emulsions, and tends to decrease the tendency of the droplets to form low resistance paths between the electrodes. Even if the 30 direct current component is not made sufficiently large to move the curve entirely to one side of the zero axis, advantageous results will still accrue. If this is done the curve will not be symmetrical with respect to the zero axis. Instead, 35 the positive portions of the curve lying above the zero axis will have a different effective voltage from the negative portions lying therebelow. Heretofore in the electrical treatment of emulsions the effective voltages of the positive and 40 negative portions of the wave form have been maintained substantially equal. To make these effective voltages unequal is to set up an unbalanced alternating potential which exerts an unbalanced effect on a dispersed droplet in the field, 45 this action tending to accelerate coalescence and removal of the dispersed phase.

My experiments have shown that the effectiveness of the treatment is dependent upon the frequency developed by the alternator 45. No invariable rule can be given in this regard, but it has been found that there is an optimum frequency at which each individual emulsion treats most effectively. This optimum frequency can be determined by methods of trial and error. 50 This optimum frequency depends upon the values of dielectric constant and resistivity of the oil and brine components of the emulsion and upon the percentage and particle size of the dispersed phase and upon the surface and interfacial tensions of the two components, which properties of the system to be treated in part determine the resonance frequency of the globules of the dispersed phase, it being understood that the term "resonance" means that frequency at which the 55 rhythmic distortions of the droplets under the action of the alternating component of the applied field occur essentially in synchronism with the free vibration rate of the droplets. In view of the fact that the electrostatic capacity and 60 resistance of an emulsion system are complex and as yet imperfectly determined functions of the above-stated properties and proportions of the components of the system, as well as functions 65 of the dimensions and relative sizes of and gap be- 70 75

tween the electrodes defining the treating space, and since these properties are also variable functions of the potential gradient and frequency applied, it will be understood that no categorical statement of the optimum frequency for treatment of an emulsion can be made, but that this frequency depends upon the manner in which the specific properties of each system cooperate to determine the resonant frequency of the droplets of the dispersed phase.

So also there is a variation between emulsions in so far as the potential supplied from the alternator 45 is concerned. No fixed rules can be given with regard to the value of this potential, but with a given emulsion successive trials will indicate the optimum potential at which best results are obtained, this optimum potential being that potential at which sufficient distortion of the droplets, by induced charging, is effected to enable contact and coalescence of the droplets of the dispersed phase, without producing such excessive distortion as to cause additional dispersion of the droplets. Thus, if the potential were raised too high an individual droplet would be elongated to such an extent that it would divide into two droplets, an effect that must usually be avoided if best treating action is to be effected. As will be appreciated, without extended discussion, significantly lower potentials will be satisfactory in producing sufficient distortion of the droplets if the frequency of the alternating component has the optimum value.

Since, also, as has been previously stated and as is disclosed in the patent to Cottrell, No. 987,115, the resistance of an emulsion is a function of the potential gradient to which it is subjected and as the resistance of the emulsion is also a function of the frequency of the alternating component of the applied field, it is immediately obvious that the simultaneous application of a direct current potential, superimposed upon the alternating current potential, will operate to alter the optimum frequency and optimum potential which would exist for alternating fields alone. It therefore is apparent that the simultaneous application of the direct current potential, in effect, serves to alter the apparent properties of the emulsion system, so as to permit the alternating field to exert a resolving effect upon the emulsion of which it would not alone be capable.

It should also be noted that a further factor, in determining the frequency and potential of the alternating component and the potential of the direct potential component which together yield optimum results in resolution of the emulsion, resides in suitable choice of the conditions of fluid flow and agitation in the treating space. This arises from the fact, as my experiments have proved, that the conditions of flow and agitation to which the emulsion system is subjected while in the treating space in part determine the resistance and electrostatic capacity of a given system and hence operate to partially determine the resonance frequency of the droplets of the dispersed phase, as well as to affect the degree of distortion of those droplets under a given instantaneous potential gradient. This arises from the obvious fact that the isotropic properties of a heterogeneous liquid system at rest are, in part, altered to anisotropic properties when such a system is subjected to suitable conditions of flow and agitation.

If the commutating device 52 is operated, it will be clear that only a portion of the wave form

shown in Fig. 3 will be impressed on the electrodes. Thus, if the commutating device 52 is operated synchronously with the alternator 45, it is possible to apply only the peaks of the wave shown in Fig. 3. By changing the phase relationship between the commutating device 52 and the alternator 45 any portion of the wave can be impressed across the electrodes. In other instances the commutator device 52 may be operated promiscuously, in which event the wave form applied to the transformer 61 will be of irregular shape.

The advantage of thus intermittently breaking the current to the transformer 61 is twofold. In the first place, it will be clear that each time the commutator device 52 closes its contacts, the voltage across the primary of the transformer 61 will be quickly increased from zero to the value of the potential supplied by the alternator at this instant. This will result in a steep wave-front surge to the transformer, this surge being transmitted to the electrodes. Such a steep wave-front has been found to give very desirable results and is especially valuable in decreasing the short-circuiting tendency of the treater. In the second place, however, this commutator device permits the condenser 66 to be intermittently charged and discharged. Thus, during the time that the transformer 61 is energized, the condenser 66 will be charged. When, however, the commutator device 52 breaks the circuit to the transformer, the previously charged condenser will discharge in the input circuit 60 and will send a steep wave-front surge to the electrodes. The input circuit 60 may be designed so that the discharge therein is aperiodic, in which event the condenser will send a single steep wave-front surge to the electrodes, but will not set up oscillatory currents in this input circuit. On the other hand, by suitably adjusting the condenser 66 with respect to the other impedances in the input circuit 60, this circuit can be designed so that a high frequency oscillation is set up therein at the time the commutating device 52 breaks the circuit to the transformer. In either event, breaking of this circuit will cause the condenser 66 to discharge to set up one or more steep wave-front surges in the input circuit 60.

In Fig. 5, I have illustrated another form of the invention in which the electrodes 11 and 12 are connected in an input circuit 80 including a transformer 81. This transformer may be of the conventional two-winding type or may be in the form of an auto-transformer. In either event, it will include a primary winding 82 and a secondary winding 83. In the form of the invention shown the primary and secondary windings are connected together and grounded as indicated by the numeral 84, the electrode 11 being also grounded. A conductor 85 connects the electrode 12 to the high voltage terminal of the secondary winding 83 and a control resistance 86 is preferably connected in series with this conductor, though in many instances this resistance can be eliminated.

The grounded terminal of the primary winding 81 is connected to a conductor 90 which is in turn connected to one conductor of a supply line 91 comprising a source of potential. The other terminal of the primary winding 82 of the transformer is connected to a conductor 94 in which is positioned a resistance 95 and a condenser 96. This conductor is connected to the supply line 91 through a winding 98 which preferably surrounds a core 99 whereby this core is magnetized when

current passes through the conductor 94. An auxiliary circuit 100 is connected between the conductor 90 and the line-side of the condenser conductor 96, this auxiliary circuit including a switch 101 which, in conjunction with the winding 98 and core 99, forms a vibrator means well-known in other arts. The switch is shown as including a pivoted armature 102 adapted to engage and disengage a contact 103, being normally held against this contact as by a spring 104. When, however, the current through the winding 98 becomes sufficiently large, the core 99 will act as a magnet to draw the upper end of the armature 102 leftward to break contact with the contact 103.

In considering the operation of this form of the invention, let it be assumed that the switch means 101 is open. At this time current from the supply line will flow through the winding 98 and through the conductor 94 and will simultaneously charge the condenser 96 and energize the transformer 81, the current returning to the supply line through the conductor 90. The energization of the primary winding 82 will, of course, energize the secondary winding 83, thus impressing across the electrodes 11 and 12 a potential dependent upon the potential of the supply line. When, however, the armature 102 comes into engagement with the contact 103 the circuit conditions are entirely changed. At this time the auxiliary circuit 100 is connected directly between the conductors 90 and 94 so that current from the supply line moves through the winding 98 and through the auxiliary circuit 100 returning through the conductor 90. The winding 98 acts as a choke in this regard and the impedance of this winding may be sufficient to prevent excessive current flowing at this time. In addition, however, a resistance 106 may be positioned in the conductor 90 to further limit this current flow if desired.

Considering the conditions which take place on the load side of the switch 101 when the contacts of this switch close, it will be clear that two things simultaneously occur. In the first place, the closing of the switch 101 isolates the load with respect to the supply line so that the potential previously applied from the supply line is cut off. In the second place, as soon as the switch 101 closes, the condenser 96 discharges into the input circuit of the treater. Considering the latter phenomenon in detail, it will be clear that the energy previously stored in the condenser 96 will be dissipated in the form of one or more steep wave-front surges of current which flow through the closed circuit including the switch 101, the primary winding 82, and the resistance 95. Whether or not this circuit is aperiodic will depend upon the characteristics of the elements therein. By particular design the condenser may be made to send only a single surge through the primary winding 82 of the transformer. On the other hand, it is possible to design this closed circuit so that an oscillatory high frequency current will be set up therein in which event a series of steep wave-front surges will be delivered to the primary winding 82. It will be clear that these surges are transmitted to the secondary winding 83, and thus delivered to the electrodes 11 and 12.

It will be clear that the armature 102 will be actuated in response to the current flowing through the winding 98. The circuit is so designed that the magnetic pull of the armature 99 when in circuit with the condenser 96 and the primary winding 82 will be insufficient to draw

the armature 102 leftward, and under these circumstances the armature will move into engagement with the contact 103. As soon as this engagement takes place the current through the winding 98 is greatly increased and as soon as the magnetic flux builds up sufficiently the armature 102 will be drawn leftward to open the switch 101.

The supply line 91 may be energized either by a unidirectional or alternating potential. If connected to a source of unidirectional potential, the wave form developed between the electrodes 11 and 12 will be somewhat as shown in Fig. 6. The instant of time when the armature 102 breaks contact with the contact 103 is indicated by the dotted line 110, the instant of time at which these members come into engagement being indicated by the dotted line 111. Thus, during the interval of time between these instants and indicated by the letter A, the condenser 96 will be charging, and a small current will pass through the winding 82 of the transformer which will in turn induce a relatively small potential across the electrodes 11 and 12, as shown by that portion of the curve below the zero axis. As soon as the armature 102 engages the contact 103 the condenser discharges, sending a steep wave-front surge through the winding 82 and inducing in the winding 83 a corresponding steep wave-front surge indicated by the numeral 113. If the circuit is properly designed only one surge will take place before the armature 102 breaks contact with the contact 103 at an interval of time indicated by the numeral 114. Thus, during the interval B a single steep wave-front surge will be impressed across the electrodes.

If, however, the circuit is so designed as to have oscillatory characteristics, this single surge will be replaced by a series of high frequency surges which may take the wave form shown in Fig. 7, the interval A indicating the period of charge of the condensers, and the interval B indicating the period during which the condenser discharges so as to set up a plurality of steep wave-front surges 118 during this interval.

If the supply line 91 is connected to a source of alternating potential, the wave form will be somewhat different, Fig. 8 roughly indicating one form which this potential may assume. Here the letter A represents the interval of charge of the condenser, while the interval B represents the interval during which the condenser discharges to set up a single steep wave-front surge 120 across the electrodes. The subsequent period of charging of the condenser 96 is indicated by the letter A', while the subsequent period of discharge is indicated by the letter B' and produces a steep wave-front surge 121. The second surge will be in the opposite direction from the first surge if the switch means 101 is operated at double the frequency of the incoming alternating potential. If this switch means operates promiscuously, the wave form shown in Fig. 8 will be somewhat varied depending upon the portion of the alternating current cycle upon which the switch means 101 closes and opens.

In Fig. 9 I have illustrated the action which takes place if an alternating current is supplied and if the circuit including the winding 82, the condenser 96, and the switch means 101 is of an oscillatory character. Here during the interval B or B' representing the periods during which the switch means 101 is closed, a plurality of steep wave-front surges 122 will be impressed across the electrodes. Stated in other words, an

oscillating current of high frequency will flow through the circuit and will induce high frequency surges of steep wave-front across the electrodes. The wave-front obtainable will, of course, depend upon whether the switch means 101 is closed synchronously or promiscuously. In the latter event, the wave form shown in Fig. 9 will be somewhat different.

In Fig. 10, I have shown an alternative mode 10 of connection in which the supply line is indicated by the numeral 130. A conductor 131 is in series with the resistor 132 and conducts current to a winding 133 of the transformer 134, as previously described, the higher potential being obtained across a winding 135 of this transformer and being transmitted to the electrodes 11 and 12, as previously described. A conductor 137 is connected to both the windings 133 and 135 and is also grounded, this conductor extending to a switch means 138 similar to the switch means 101 previously described and including a winding 139 for moving an armature 140 of this switch means to make and break contact with a contact 141. The latter contact is connected through a conductor 142 to the winding 139 which is in turn connected to the line 130, as shown. A conductor 142 extends between the conductors 131 and 144 and includes a condenser 145 and a resistor 146 in series therewith.

It will thus be clear that when the switch means 138 is closed current may flow through two parallel paths. The first of these may be termed a main circuit and includes the resistor 132, the conductor 131, the winding 133, the conductor 137, the switch means 138, the conductor 142, and the winding 139. The second may be termed a supplementary circuit and includes the resistor 132, the conductor 131, the resistor 146, the condenser 145, the conductor 142, and the winding 139. The relative amounts of the current flowing through these circuits is dependent upon the relative impedances thereof. Usually the current flowing through the winding 133 is greater than that flowing through the conductor 144, though this is not necessarily the case in all instances. In any event the combined current is sufficient to draw the armature 140 leftward to disengage the contact 141 at which time the voltage across the condenser 145 increases and this condenser is further charged, the winding 133 being de-energized by this opening of the switch means. However, the current flowing through this condenser is insufficient to maintain the armature 140 in its new position so that this armature falls back and again engages the contact 141. At this instant the potential of the supply line 130 is again placed across the winding 133 and it will also be clear that the condenser 145 will discharge through a closed circuit including this condenser, the switch means 138, and the winding 133. The sudden closing of the switch 138 will thus not only set up a steep wave-front surge in the winding 133 due to the potential of the supply line, but will also set up a surge from the condenser 145 of much greater magnitude. The resultant surge is impressed across the electrodes 11 and 12 to produce the desirable treating action hereinbefore described.

The switch means 138 may be operated either synchronously or promiscuously, as previously set forth, and the supply line 130 may be energized either by unidirectional potential or alternating potential. The wave forms obtained will be of the same general nature as those shown in

Figs. 6 to 9 inclusive, varying in slight details, due to the fact that in the form of the invention shown in Fig. 10 the closing of the switch 138 has the dual function of energizing the winding 133 and transmitting the condenser surge there-through.

From a comparison of Figs. 1, 5, and 10, it will be clear that the condenser which is intermittently charged and discharged may be either directly in series with the electrodes or in series with one winding of a transformer energizing these electrodes. In either event this condenser is in series with the input circuit connected to the electrodes. This input circuit thus includes conductors connected to the electrodes, or may include these conductors and the transformer (if one is used), the condenser discharging thereto in either instance. It should thus not be understood that I am limited to any particular placement of the transformer utilized, for this transformer may be positioned either on the load side of the condenser or on the line side thereof.

Various other modifications will be apparent to those skilled in the art and fall within the scope of this invention.

It will be clear also that the invention may be utilized in conjunction with other known types of dehydrating methods and apparatus, in which event these auxiliary features often serve to increase the treating action on emulsions otherwise hard to treat.

The present invention is a continuation-in-part of my co-pending application Serial No. 363,197, filed May 15, 1929, entitled "Process and apparatus for separating emulsions".

I claim as my invention:

1. A method of treating an emulsion by the use of a pair of electrodes defining a treating space, which method includes the steps of: continuously superimposing on an alternating potential of primary wave form a single alternating potential of secondary wave form and of higher frequency than said alternating potential of primary wave form to form a rippled wave form composed of a lower-frequency wave on all portions of which is impressed a single higher-frequency wave; impressing the resultant potential between said electrodes; and subjecting the emulsion to be treated to the action of the electric field thus set up between said electrodes.

2. A method of treating an emulsion by the use of a pair of electrodes defining a treating space, which method includes the steps of: applying a potential of varying magnitude across said electrodes; electrically biasing said electrodes by impressing a unidirectional potential across said electrodes of a magnitude greater than the maximum magnitude of said potential of varying magnitude whereby the potential across said electrodes never becomes zero during the energization of said electrodes, said potential across said electrodes being of sufficient intensity to coalesce the dispersed particles of said emulsion; and subjecting the emulsion to be treated to the electric stress set up in said treating space to coalesce said dispersed particles without reversal of the charges on a particular dispersed particle at the ends thereof toward said electrodes.

3. In an electric treater for treating emulsions, the combination of: a pair of electrodes defining a treating space containing the emulsion to be treated; a transformer connected to said electrodes; a condenser in circuit with said trans-

former and storing electric energy during the time said transformer is energized; a source of potential; and switch means for periodically energizing said transformer from said source of potential and subsequently deenergizing said transformer to permit said condenser to discharge to set up a steep wave-front surge to said electrodes.

4. In an electric treater for treating emulsions, the combination of: a pair of electrodes between which is positioned the emulsion to be treated; a potential supply means; a condenser connected in circuit with said potential supply means; an input circuit connected to said potential supply means through said condenser and connected to said electrodes to set up an electric field therebetween; an auxiliary circuit connecting said condenser in closed circuit with said input circuit whereby said condenser can discharge into said input circuit through said auxiliary circuit; and a switch means in said auxiliary circuit for periodically closing same to discharge said condenser into said input circuit.

5. In an electric treater for treating emulsions, the combination of: a pair of electrodes between which is positioned the emulsion to be treated; a potential supply means providing a pair of conductors; a transformer connected to said electrodes and supplied with current from said potential supply means; a condenser connected to said transformer, the line side of said condenser being connected to one of said conductors; and switch means for periodically connecting the line side of said condenser to said transformer to discharge said condenser into said transformer to send a steep wave-front surge to said electrodes.

6. In an electric treater for treating emulsions, the combination of: a pair of electrodes between which is the emulsion to be treated; a transformer providing a primary and a secondary winding, said secondary winding being electrically connected to said electrodes to build up a potential difference therebetween; a condenser; means for charging said condenser; and switch means operating periodically and connecting said condenser in closed circuit with said primary winding whereby the charge on said condenser is delivered to said primary winding to provide a steep wave-front surge to said electrodes.

7. In an electric treater for treating emulsions, the combination of: a pair of electrodes between which is positioned the emulsion to be treated; a potential supply means providing a pair of conductors; a magnetic means including a winding in circuit with one of said conductors; a switch means operated in response to the current flowing through said winding and connected to said winding and to the other of said conductors; a switch means whereby current flows through said winding and said switch means in series when said switch means is closed; an input circuit connected to said electrodes; condenser means connected to said input circuit to discharge therein; and means connecting said input circuit and said condenser across said switch means whereby closing of said switch means discharges said condenser therethrough and into said input circuit.

8. In an electric treater for treating an emulsion, the combination of: a pair of electrodes between which is positioned the emulsion to be treated; a source of alternating potential; a source of unidirectional potential delivering a unidirectional potential of a magnitude greater than the peak potential of said alternating potential; means for connecting said source of al-

ternating potential and said source of unidirectional potential to said electrodes whereby the resultant potential difference between said electrodes never drops to zero during the application of said potentials and means for periodically isolating one of said sources from said electrodes for only a short period of time during the time said other source is connected thereto.

9. A method of electrically treating an emulsion between electrodes, which method includes the steps of: applying an alternating potential across said electrodes; electrically biasing said electrodes by applying thereto a unidirectional potential; and periodically disconnecting and reapplying one of said potentials to said electrodes while the other potential remains applied thereto.

10. A method of electrically treating an emulsion between electrodes by the use of a source of alternating potential and a condenser, which method includes the steps of: energizing said electrodes and charging said condenser by connecting said source of alternating potential thereto; then isolating said source of alternating potential from said electrodes; and discharging said condenser to said electrodes during said isolation of said source of alternating potential therefrom whereby said emulsion is first subjected to a field set up between said electrodes by said source of alternating potential and is then subjected to a steep wave front surge developed by the discharge of said condenser.

11. A method of electrically treating an emulsion between electrodes by the use of a source of alternating potential and a condenser, which method includes the steps of: energizing said electrodes and charging said condenser by connecting said source of alternating potential thereto; then simultaneously isolating said source of alternating potential from said electrodes and discharging said condenser thereto to form a surge to said electrodes at the extreme end of the period of application of said alternating potential whereby said emulsion is first subjected to a field set up between said electrodes by said source of alternating potential and is then immediately subjected to a steep wave front surge developed by the discharge of said condenser; and subsequently re-energizing said electrodes and said condenser.

12. A method of treating an emulsion between electrodes, which method includes the steps of: applying to said electrodes an alternating potential; simultaneously electrically biasing said electrodes by applying thereto a rippled direct current potential, the frequency of the ripple being much greater than the frequency of said alternating potential; and subjecting the emulsion to the resultant field produced between said electrodes to coalesce the dispersed phase of said emulsion.

13. A method of electrically treating an emulsion including a continuous phase with dispersed liquid particles therein, which method includes the steps of: impressing across an electrode-bounded treating space an alternating potential of a frequency substantially corresponding to the resonant free vibration rate of said particles; electrically biasing said electrodes with a unidirectional potential to produce a resultant field; and causing coalescence of said dispersed liquid particles by subjecting said emulsion to the action of said resultant field.

14. In an electric treating system for treating an emulsion, the combination of: a pair of electrodes between which is positioned the emulsion

- to be treated; a source of unidirectional potential; means connecting said source of unidirectional potential across said electrodes; a source of alternating potential; means for connecting said source of alternating potential across said electrodes; a condenser means in circuit with said last-named means and preventing any of said unidirectional potential from reaching said source of alternating potential; and means for periodically discharging said condenser means to said electrodes.
15. A method of electrically treating an emulsion between electrodes by the use of a potential source and a condenser, which method includes the steps of: charging said condenser before connecting said electrodes to said potential source; and thereafter simultaneously connecting said condenser and said potential source to said electrodes to produce a surge to said electrodes from the discharge of said condenser at the instant said electrodes are energized by said potential source, said surge dying out during the period of connection of said potential source to said electrodes.
- 20 16. In an electric treating system for emulsions, the combination of: a potential supply means; a pair of electrodes between which is positioned the emulsion to be treated; electrode-energizing conductor means acting to energize said electrode means, circuit means electrically connecting said potential supply means to said electrode-energizing conductor means; switch means connected across said circuit means; means for periodically closing said switch means to periodically shunt said circuit means to decrease the normal potential applied to said electrodes by said potential supply means; and a condenser in series circuit with said electrodes and said switch means when said switch means is closed whereby closing of said switch means also closes this series circuit to allow said condenser to discharge to said electrodes, opening of said switch means thus re-applying the normally applied potential of said potential supply means to said electrodes, said normally applied potential of said potential supply means and said surge being of sufficient intensity to coalesce the dispersed

particles forming the dispersed phase of said emulsion.

17. A method of treating an emulsion containing an aqueous phase dispersed in a continuous phase, which method includes the steps of: moving a stream of said emulsion into a treating space; coalescing the dispersed aqueous particles and causing some degree of migration thereof by establishing in said treating space an unbalanced alternating field having peak potentials on one side of the zero axis which are greater than the peak potentials on the other side of said axis, the time interval of application of the potentials on said one side being greater than on said other side; moving the treated emulsion constituents from said field before complete separation of the phase liquids has taken place; and thereafter further separating the phase liquids present in said treated emulsion constituents.

18. A method as defined in claim 17 in which said electric field is established by impressing across spaced portions of said treating space a single alternating potential and a unidirectional biasing potential of a magnitude less than the peak potential of said single alternating potential.

19. In combination in a system for treating emulsions: a pair of electrodes bounding a treating space containing emulsion to be treated; a source of potential; a condenser; circuit means connecting said electrodes, said source of potential, and said condenser to energize said electrodes and establish an electric stress in said treating space; switch means in said circuit means for charging said condenser and discharging same to said electrodes; a movable member operating said switch means; and magnetic means providing a winding in said circuit means to move said movable member in response to the current flowing in a portion of said circuit means.

20. A combination as defined in claim 3 in which said transformer includes a primary winding and a secondary winding and in which said condenser, said secondary winding and said electrodes are connected in series relationship, and in which said switch means is in circuit with said primary winding of said transformer.

CERTIFICATE OF CORRECTION.

Patent No. 2,105,614.

January 18, 1938.

CLAUDIUS H. M. ROBERTS.

It is hereby certified that error appears in the printed specification of the above numbered patent requiring correction as follows: Page 8, first column, line 39, claim 16, for the word "electrodes" read electrode-energizing conductor means; and that the said Letters Patent should be read with this correction therein that the same may conform to the record of the case in the Patent Office.

Signed and sealed this 3d day of May, A. D. 1938.

(Seal)

Henry Van Arsdale,
Acting Commissioner of Patents.
